APPARATUS FOR SYNCHRONIZING THE
SPEEDS OF POWER-DRIVEN MECHA-
NISMSEdward M. May, Detroit, Mich., assignor to Meco-
Pilot Manufacturing Company, Detroit, Mich., a
corporation of MichiganOriginal application December 30, 1946, Serial No.
719,305. Divided and this application October
3, 1951, Serial No. 249,483

1 Claim. (Cl. 74—665)

1

The invention relates to means for synchronizing the speeds of two power-driven mechanisms driven by separate motors. The present application is a division of my earlier application Serial No. 719,305, filed December 30, 1946, the motor-driven mechanisms synchronized in accordance with the present invention being a pair of the motor-driven hydraulic control mechanisms of the character disclosed in the earlier application.

It is an object of the present invention to provide a pair of the motor driven control mechanisms having hydraulic coordinating means causing the two mechanisms to operate synchronously at relative speeds which are subject to predetermination by adjustment of the apparatus.

For the attainment of the above-stated object and others of an incidental or ancillary nature the invention consists in the forms, arrangements and combinations of parts defined in the appended claim and explained in the following description of an exemplary apparatus shown in the accompanying drawings.

In the drawings,

Fig. 1 is a front elevation of a unitary control apparatus of which a plurality can be operatively combined in carrying out the present invention.

Fig. 2 is a right side elevation of the apparatus shown in Fig. 1 with a portion of the casing structure broken away to show interior parts and with hinged cover portions of the casing structure shown in closed position by full lines and in open position by dashed lines.

Fig. 3 is a view partially diagrammatic, showing the cam and hydraulic transmitter devices of the control unit in plan view on a larger scale than in Figs. 1 and 2 with some parts omitted and others shown in section, and also showing one of the hydraulically actuated elements of a turret lathe to be controlled and motor-driven pump means for supplying power liquid for the hydraulic motor of the lathe, subject to pressure control of the power liquid by the cam apparatus.

Fig. 4 is an enlarged sectional view on the broken line 4—4 of Fig. 3 with some parts of the structure broken away.

Fig. 5 is a diagrammatic view showing an operative interconnection of two hydraulic control mechanisms of the character shown in the other views constructed to secure synchronous drive of the two mechanisms.

Referring in detail to the constructions illustrated and first to the single control mechanism shown in Figs. 1-4, numeral 1 designates as an

entirety (Figs. 1 and 2) a cabinet designed to rest upon the floor and house a hydraulic transmitter apparatus in accordance with the invention. The cabinet is preferably built up of sheet steel and is fitted with a pair of bottom skids 2, 2 adapted to slide upon the floor when the apparatus is moved. The front of the cabinet may be left open as shown but the top is partially closed by cover sections 3 and 4 which are hinged on 10 the body of the cabinet at 3a and 4a, respectively, so that they can be swung downward to the positions shown in dotted lines to give free access to the apparatus within the cabinet and at the same time serve as shelves for tools and 15 parts when changes and adjustments of the apparatus are being made. The rear cover 4 is disposed at a higher level than the front cover 3 so that an inspection opening or window is provided at 5 for a purpose which will presently 20 appear. The cover 4 is formed in its top portion with an opening 4b over which are arranged an electric light bulb 6, preferably of the elongated tubular type, and a reflector 7, the purpose of the light being to illuminate parts of the enclosed 25 apparatus as viewed through opening 5.

Within the upper part of the cabinet 1 is a rectangular frame 8 secured to the walls of the cabinet by bolts or screws (not shown), the said frame being inclined downwardly from the rear to the front of the cabinet as shown in Fig. 2. 30 As best shown in Fig. 3, the rear side of frame 8 carries a series of hydraulic transmitters 9, 9 two of which have been omitted to facilitate disclosure of other parts. Each transmitter comprises a block 10 formed at its front end with a transverse cylinder chamber 11 (Fig. 4). This chamber is closed at its respective ends by heads 12 and 13. Within chamber 11 is a piston structure 14 comprising a disc 15, hydraulic packing 16 and retaining ring 17. The piston is fast on a rod 18 which is guided at one end in a boss carried by the head 12 and at its other end extends through an aperture in the head 13 fitted with a suitable hydraulic packing 19. The cylinder block 10 is formed on its top side with a threaded aperture 20 to which is connected a conduit 21 designed to connect chamber 11 with receiver apparatus which will later be described. 40

The cylinder block 10 of each transmitter is also formed with a top recess to receive an upright, open-topped tubular reservoir 22 of transparent material such as plastic or glass. The reservoir is designed to hold oil or other working liquid for the transmitter and has its joint with 45 block 10 packed to prevent leakage. Passages 23

and 24 lead from the bottom of the reservoir 22 into the cylinder chamber 11, the passage 24 communicating with chamber 11 adjacent the closure head 13 while passage 23 communicates with chamber 11 at a point intermediate passage 24 and passage 20. With this arrangement the packing 16 of the piston structure serves to close the passage 23 as the piston moves forward on its working stroke. A coil spring 25 is interposed between the piston 14 and the head 12 and is adapted to retract the piston following its working stroke.

To effect the working stroke of the piston 14 cam devices are provided comprising a horizontal cylinder 26 having a cylindrical shell 27 and end discs 28, 29 which are centrally apertured and secured by set screws or the like on a supporting shaft 29. Shaft 29 in turn is supported by anti-friction bearings 30 in the respective ends of frame 8. To permit easy removal of the cylinder structure as a unit the end sections of frame 8 are fitted with swinging bearing caps 31 which are hinged at their front ends to the frame and are disengageably secured at their rear ends by swinging bolts 32.

The cylinder 26 is formed peripherally to receive a series of circumferentially extending cams 33, 33, one for each of the transmitters 9, 9. That is to say, the cylinder has a series of circumferentially extending cam seats 27a extending radially somewhat beyond the main surface of the shell 27, and adjacent each seat surface 27a the shell is formed with a circumferentially extending shoulder 27b to engage and locate one of the cams, each of which has a straight longitudinal edge affording a reference surface to cooperate with the locating shoulder 27b. Each cam 33 is preferably formed from an elongated relatively thin strip of metal or other material susceptible of being manually bent from the flat state to circular form and preferably also possessing sufficient elasticity to return substantially to the flat state when released. Aluminum alloy sheet material of suitable temper is a satisfactory material for the purpose.

Each of the cams 33 is provided adjacent its two ends with apertures to receive securing screws 34, 34 which engage threaded holes 27c, 27c of the cylinder drum 27, and is also provided adjacent one end with a dowel hole to engage a dowel pin 35 attached to drum shell 27. Each cam may if desired be provided with additional securing screws spaced around the periphery of the cam drum. As will be apparent from Fig. 3, each of the cams 33 has one longitudinal edge formed with various lobes or active cam sections to effect desired movements of its hydraulic transmitter through the cam follower provided for that purpose. Such follower is in the form of a lever arm 36 fitted at its free end with a roller 37 to engage the cam and pivotally supported at its other end in position to engage the projecting end of the piston rod 18. The pivotal support for the arm 36 is afforded by pin 38 carried by the head of a bolt 39 having a swiveling support in the rear part of receiver block 10. With this construction the follower arm 36 can be raised when desired as indicated by dotted lines in Fig. 2 to permit removal of the cam cylinder 26 from frame 8. The swiveling bolt 39 is fitted with a washer 39a and a coil spring 40 which engages the bolt washer and yieldingly presses the head of the bolt against the adjacent face of block 10 (Fig. 3). To support the roller 37 in operative engagement with the edge of the cam 33 the side of follower arm 36

where it engages the piston rod 18 is formed with an angular groove or depression 36a as shown in Fig. 4. The engagement between the arm and the end of the rod is normally maintained by the tension of the spring 25. As is shown in Fig. 4 the follower arm 36 during normal operation lies within a slot 13a of the cylinder head 13.

For reasons later explained it is desirable to be able to adjust the transmitter blocks 10 in relation to the supporting frame 8 and to this end each block is secured to the frame by a pivot pin 41 (Fig. 4) and a clamping screw 42 which passes through a hole in the block 10 somewhat larger than the shank of the screw so that the block can be adjusted around the axis of pin 41.

Rotation of the cam drum is effected by an electric motor 43 which is connected to drive a variable speed mechanism 44 which in turn is connected through worm and wheel gears to drive a pinion 46 meshing with a spur gear 47 fast on shaft 29 of the cam drum. Preferably the motor, variable speed mechanism and worm and wheel gears constitute a unitary device which is supported on the end of cabinet 1 by a suitable bracket 48. With the described gear connection between the motor and the cam drum the removal of the latter from its supporting frame involves merely the disengagement of the bearing caps 31 and separation of spur gear 47 from the driving pinion 46. For control of motor 43 it is connected in circuit with switch and relay devices 49 and 49', respectively, of well known construction, the switch having a starting button 49a and a stop button 49b. Further reference will be made to these manual control devices later in the description.

The apparatus is further provided with safety devices comprising an emergency switch 50 which is connected in circuit with motor 43. Switch 50 is normally held in its closed position by means of a double-ended dog 51 fixedly secured to a rod 52 which is slidably mounted in bracket 53 and 54 attached to the frame 8 (Fig. 3). Dogs 55, 55 are adjustably clamped on rod 52, each a little to the right of the head of one of the pivot bolts 39. A coil spring 56 which is interposed between one of the dogs 55 and bracket 54 urges rod 52 toward the left. Rotation of the rod 52 is prevented by the disposition of the arms of dog 51 adjacent the horizontal surface of the bracket 53. With this arrangement if the discharge of any one of the transmitters should be blockaded or movement of the cam follower be in any way obstructed the spring 40 of the pivot bolt will yield and permit the follower arm 36 to swing about the end of piston rod 18 as a pivot with resultant movement of the sliding rod 52 toward the right and the opening of emergency switch 50.

With the hydraulic transmitters actuated by the circular or endless form of cams it is apparent that a cycle of transmitter movements is effected for each rotation of the cam drum 26. For the control of some types of machines and operations it may be desirable for the control mechanism, when started manually by switch button 49a, to run continuously for the performance of a considerable number of control cycles and then be stopped by manual switch button 49b. In other cases, however, it may be desirable to stop the control mechanism at the end of each cycle and have the apparatus started again manually. To this latter end means are provided to open emergency switch 50 at the end of each rotation of the drum 26. Said means comprise a lever arm 57 fitted at its front

end with an antifriction roller 53 arranged to be engaged by a radial pin 59 carried by cylinder 26. At its rear end the arm 57 is slotted to receive the end of eye bolt 60 to which the arm is pivotally connected by pin 61. Bolt 60 has a swiveling support in block 62 carried by frame 8 and is fitted at one end with a washer 63 which is engaged by spring 64 to hold the arm 57 yieldingly against the side surface of block 62. The rear end of arm 57 is engaged by the front end of dog 51 on the sliding rod 52 and normally serves as a positive stop limiting movement of rod 52 by spring 56. With this construction when the control apparatus is started by actuation of the starting switch 43a the cam drum 26 rotates, in the direction of arrow R, until pin 53 engages roller 53 to swing the arm 57 around the right front corner of block 62 as a pivot with resultant movement of the rear end of arm 57 to the right. This movement carries dog 51 to the right and opens emergency switch 58 to stop the drive motor 43.

In order to insure the proper positioning of roller 53 in relation to the pin or dog 59, block 62 is adjustably secured to frame 8 by means of pin 65 and clamping screw 66, the clamping screw having a sufficiently loose fit in the block to permit the relatively small range of needed adjustment. When multiple cycle operation without manual control is desired it is only necessary to block up arm 57 to remove roller 53 from the path of dog 59, such positioning of arm 57 being permitted by the swivel mounting of bolt 60.

An additional motor control switch 67 is mounted on bracket 53 with its actuating arm disposed adjacent the rear end of arm 57. The switch which is normally open, is closed by the above described swinging movement of arm 57. The purpose of switch 67 will appear at a later point in the description.

It is desirable that the stopping of the cam mechanism be effected without any considerable overrun when the control switch is actuated. To this end the motor 43 is preferably equipped with a magnetic brake so that it will stop promptly when deenergized. Alternatively (and at less cost) use may be made of well known switch and relay circuit means adapted to give the desired quick stopping.

The invention contemplates automatic control of the variable speed mechanism 44 through which motor 43 is connected to drive the cam drum 26. To this end gearing 44 is provided with a crank arm 44a connected to actuate the speed varying means of the mechanism. As has been stated any suitable form of speed varying mechanism can be employed but that manufactured by Graham Transmissions Inc., of Milwaukee, Wisconsin, and shown in U. S. Patent No. 2,405,957, has been found satisfactory for use. Crank arm 44a is actuated by a hydraulic receiver comprising cylinder 68 and piston 69 having a rod 70 with a pin and slot connection to arm 44a. One end of cylinder 68 is connected by a conduit 21 with one of the hydraulic transmitters 9. Thus the hydraulic impulse of the transmitter serves to move the piston 69 against the tension of a retracting spring 71 interposed between the piston and one end of cylinder 68. The speed change mechanism and the connections between it and arm 44a are such that the piston movement opposed to spring 71 increases the speed transmitted through pinion 46 and gear 47 to the cam drum. Movement of piston 69 in the reverse

direction by spring 71 correspondingly reduces the speed transmitted to the cam cylinder. To determine the maximum and minimum speeds which may be thus automatically provided by the hydraulic mechanism adjustable screws 72, 73 are mounted on bracket 73 carried by the casing of mechanism 44 and serve to limit the swinging movement of lever 44a.

By means of the described hydraulic devices for determining the speed of rotation of the cam drum 26 it is possible by the provision of a suitably shaped cam for actuating the transmitter connected to cylinder 68 to vary the speed of cam movement at will throughout the cycle of rotation of the cam drum.

In Fig. 3 of the drawings is shown more or less diagrammatically a machine element, hydraulic motor devices and pressure fluid supply means for the motor devices connected in a typical manner to the hydraulic transmitter control mechanism already described. The machine element 74 may be taken as a portion of the turret slide of the turret lathe shown in Fig. 6 of the aforementioned earlier application, Serial No. 719,305. Associated with the slide is a hydraulic motor comprising a cylinder 75 anchored at 76 and having a piston 77 with rod 78 connected by arm 79 to the slide element 74. This hydraulic motor is fitted with a hydraulically actuated control valve of the follow type. The valve comprises a casing 80 providing a chamber 80a for a spool valve 81 and a chamber 80b for an actuating piston 82 having its rod 83 extending into chamber 80a to urge the valve 81 toward the right against the tension of spring 84. The chamber 80b is connected on the left side of piston 82 with one of the conduits 21 leading to one of the hydraulic transmitters 9. Piston rod 78 of the main motor carries an arm 85 to which is attached a follow rod 86 extending into chamber 80b. The latter chamber, on the right side of piston 82, is open to the atmosphere through vent 87 so that no working fluid for the main motor can leak past the packing of rod 83 and affect the control piston.

A pump 88 of constant delivery type is directly driven by motor 89 mounted upon the top of a sump chamber 90. The pump has its intake connected by a suction pipe 91 with the interior of sump 90 and has a discharge pipe 92 with various branches to supply a plurality of hydraulic motors. One such branch 92a is shown connected to the inlet port of valve casing 80. The right end of the control valve chamber 80a discharges to a return pipe 93 delivering into sump 90. Pipe 93 may also have branch return lines leading into it as indicated in Fig. 3.

To control the pressure of the working fluid delivered to the hydraulic motor or motors served by it discharge pipe 92 is fitted with a by-pass valve 94 of well known construction. To effect variation in the pressure of the working fluid supplied to the controlled motor or motors valve 94 is equipped with relief valve devices comprising casing 95, ball valve 96 and coil spring 97 which yieldingly urges the valve against the inlet port of casing 95, the outlet port being connected by conduit 98 to sump 90. To automatically vary the tension of spring 97 casing 95 is provided with a chamber 99 for hydraulic piston 100 having a rod 101 engaging the end of spring 97. With chamber 99 connected as shown through a conduit 21 with one of the hydraulic transmitters 9 the impulse of the transmitter, determined by its actuating cam, serves to vary the tension of

spring 97 and hence the pressure at which the valve 96 opens to control the opening of by-pass valve 94. Casing structure 95 is provided with a relief port 102 on the right side of piston 100.

From what has been said it is apparent that the control apparatus is adapted automatically to control the amounts or distances of the power-driven movements of one or more machine elements, to control the pressure of the working liquid supplied to the motor or motors of the machine elements during or in different parts of the movements of the said elements to thereby vary the force of the individual movements, to control the sequence in which the movements of the machine elements occur and also to control the speed with which the cycle or cycles of machine element movements, or parts of such cycles, are carried out.

Fig. 5 of the drawings shows how two of the motor-driven control units, designated "Director A" and "Director B" can have their speed control cams coordinated to operate the directors at synchronous speeds, which may be either equal or different. This is accomplished by connecting the transmitter 9 of director A through conduit 21 to the speed control cylinder 68 of the director and the transmitter 9' of director B through conduit 21' to conduit 21, so that both transmitters are connected to the same speed control cylinder. The control arm 44a' of director B is locked by limit screws 72' in fixed position for a relatively low speed. The adjusting screws 72 of transmitter 9 are positioned to permit a relatively small movement of arm 44a in a range corresponding to a higher speed than that of director B. The receiver piston 69 of director A is required only to correct variations from synchronous speed and relatively small movement of arm 44a is sufficient for this purpose. Accordingly the displacement incident to movement of piston 69 is small compared to the displacement of transmitters 9 and 9'.

The speed control cams 33 and 33' of the two directors are formed so that director A must make two revolutions for one of director B. Therefore when the lever 44a' is set to speed, lever 44a must be set to twice that speed but with a limited range of movement to allow piston 69 to adjust for departure from synchronism.

As the cams revolve in the direction of arrow R follow arm 36' rises and transmitter 9' forces liquid into the common pilot conduit system. At the same time arm 36 falls and transmitter 9 withdraws an equal amount of liquid from the system. Therefore no movement of piston 69 occurs. It will be observed that the rise on cam 33' between 0 and 10 equals the fall of cam 33 between 0 and 20. Suppose, now, that cam 33 turns too fast. Then transmitter 9 will remove

oil faster than transmitter 9' supplies it and piston 69 will move lever 44a toward the left to a lower speed position, thereby correcting the overspeed. Conversely underspeed of director A will move arm 44a to the right to bring the speed up to synchronism with director B.

It is a peculiarity of the described system that the regulating action operates only when cam 33 is falling and cam 33' rising. Therefore there is a period of lost control while arm 36 rises and arm 36' falls. This period is made as short as possible as shown by lobe 33a of cam 33. Also advantage of this period is taken to refill the pilot system by providing filler notch 118. The departure from speed during this period is toward making director A run too slow but the discrepancy is limited by screw 72 on the low side of the control arm. Synchronous position and speed are quickly regained as soon as arm 36' is rising and arm 36 falling, so that the cycles of the two directors always end together.

In the foregoing disclosure the invention is applied to motor-driven control mechanisms but it will be apparent that the cam driven hydraulic interconnection of the synchronized motors can be applied to other kinds of motor driven units to effect their synchronization. Furthermore, it is to be understood that forms of construction varying, within the bounds of the following claim, from those herein disclosed can be used in the practice of the invention.

What is claimed is:

In automatic apparatus, the combination of two mechanisms each comprising a motor drive device having means for varying its speed; manual means for adjusting and setting the speed-varying means of the first mechanism to determine the speed of that mechanism; and automatic means for adjusting the speed-varying means of the second mechanism to determine the speed of the second mechanism in relation to the speed of the first mechanism, said automatic means comprising for each mechanism a hydraulic transmitter having a cylinder, a piston therein, and a rotary cam driven by the drive device of the mechanism for actuating the transmitter piston and comprising further a hydraulic receiver cylinder, conduit means connecting both of the hydraulic transmitters to the inlet of the receiver cylinder and a piston in the receiver cylinder operatively connected to the speed-varying means of the second mechanism, the cam of the second mechanism having predominantly a falling slope while the cam slope of the first mechanism is predominantly rising to complement the slope of the other cam.

EDWARD M. MAY.
